Des. 181,150
Patented Oct. 8, 1957

181,150

COMBINED MIRROR AND NAME PLATE

Max B. Horn, Whittier, Calif.

Application August 22, 1955, Serial No. 37,601

Term of patent 14 years

(Cl. D33—9)

Figure 1 is a perspective view of the mirror side of my combined mirror and name plate;

I claim:

The ornamental design for a combined mirror and name plate, substantially as shown.
